UNITED STATES PATENT OFFICE.

EDWIN W. MCKINLEY, OF NEW YORK, N. Y.

ELECTRIC SIGNAL.

Application filed July 7, 1923. Serial No. 650,088.

To all whom it may concern:

Be it known that I, EDWIN W. MCKINLEY, a citizen of the United States, residing at New York city, in the county of New York and State of New York, have invented certain new and useful Improvements in Electric Signals, of which the following is a specification, reference being had to the accompanying drawings.

10 This invention relates to certain improvements in signals and has relation more particularly to a device of this general character especially designed and adapted for use in connection with motor vehicles or the 15 like giving various traffic warnings such as indicating the intention of stopping or to indicate the direction in which a turn is to be made.

Another object of the invention is to provide 20 a novel and improved device of this general character comprising a single plate having produced thereon portions through which light rays are adapted to be emitted, said portions being so arranged and assembled to provide a composite of a plurality of indications or symbols such as the words Rite, Left and Stop together with means whereby parts of said portions may be selectively illuminated to bring one of 25 such indications or symbols into conspicuity.

The invention consists in the details of construction and in the combination and arrangement of the several parts of my improved signal whereby certain important advantages are attained and the device rendered simpler, less expensive and otherwise more convenient and advantageous for use, as will be hereinafter more fully set 35 forth.

The novel features of my invention will hereinafter be definitely claimed.

In order that my invention may be the better understood, I will now proceed to describe the same with reference to the accompanying drawings, wherein:—

Figure 1 is a view in rear elevation of a vehicle having applied thereto a signal constructed in accordance with an embodiment 50 of my invention and operating to bring a single indication or symbol into conspicuity;

Figure 2 is a view in elevation of the member to be assembled within the casing and which is provided with separate compartments each containing an independent illuminating member;

Figure 3 is a sectional view taken through the complete device and on substantially the line 3—3 of Figure 2;

Figure 4 is a sectional view taken through the complete device and on substantially the line 4—4 of Figure 2;

Figure 5 is a sectional view taken through the complete device and on substantially the line 5—5 of Figure 2;

Figure 6 is an enlarged view in front elevation of the device as herein disclosed and particularly illustrating the composite indication or symbol, the compartments and illuminating members associated therewith being indicated by broken lines;

Figure 7 is a view in front elevation of the signal as herein disclosed showing the same illuminated to exhibit one indication;

Figure 8 is a view in front elevation of the signal as herein disclosed showing the same illuminated to exhibit a second indication;

Figure 9 is a view in front elevation of the signal as herein disclosed showing the same illuminated to exhibit a third indication.

As disclosed in the accompanying drawings, my improved signal comprises a casting C of requisite dimensions and configuration and in which snugly fits a unit A providing a series of lamp compartments 1, 2, 3, 4, 5, 6, 7, 8, 9, 10, 11, 12, 13, 14 and 15 of irregular shape. The rear or inner wall of each of the compartments is provided with a lamp socket 16. Overlying the outer open faces of the unit A is an opaque plate 17. This plate 17 has provided thereon portions arranged to provide a composite of a plurality of indications or symbols said portions in the present embodiment of my invention constituting openings affording a composite of the words Rite, Left and Stop.

The left end portion of the plate 17, as herein disclosed, is provided in its upper part with an angular opening comprising the horizontally disposed parallel portions a and b connected at their outer ends by a vertically disposed portion c. The inner end of the portion b is continued by the depending vertical portion d while the inner end of the portion a is continued by a short depending portion e. The portions a, b, d and e overlie the compartment 2 while the portion c overlies the compartment 1. Also overlying the compartment 1 and below the portion c and substantially coplanar

therewith is a vertically disposed slot *f*. At a point below the portion *d* of the first named slot and substantially parallel therewith and extending from the lower portion 5 of the slot *f* and terminating below the portion *d* is a slot *g*, said slot *g* overlying the compartment 3 and a portion of the compartment 5 partially underlying the compartment 2.

10 A vertically disposed slot *h* is provided in the plate overlying the inner portion of the compartment 5 and extending substantially entirely thereacross and at opposite sides of the portion of the slot *h* are the 15 slots *i* and *j*, the slot *i* overlying the compartment 4 and the slot *j* overlying the compartment 7, a portion of the compartment 5 extending between the compartments 4 and 7. The plate 17 is provided with vertically spaced and horizontally disposed slots *k* and *m* overlying the compartment 6 and having their inner ends immediately adjacent to the slot *h*, the lower slot *m* being of a length greater than the slot *k* and 25 substantially co-extensive with the slot *j*.

The plate 17 is provided with a slot *n* overlying the compartment 9, said slot being substantially in the form of an inverted L, and the slot *o* overlying the compartment 30 8 and substantially coplanar with the slot *j* and the upper or leg portion of the slot *n*. The plate is also provided with the relatively short slot *p* overlying the compartment 10 and positioned at substantially the 35 central part of the inner portion or stem of the slot *n*. Overlying the compartment 11 is a slot *q* in the form of a reversed L and also with the short horizontally disposed slot *r* overlying the compartment 12 40 and positioned at the upper extremity of the vertical portion of the slot *q*. A slot *s* also substantially in the form of an inverted L, overlies the compartment 13 and a slot *t* in the form of a reversed L overlies the 45 compartment 14, the foot of the slot *t* being toward approximately the central part of the vertical portion or stem of the slot *s*. Coplanar with the foot of the slot *t* and interposed therebetween and between the 50 vertical portion or stem of the slot *s* is a slot *u* overlying the compartment 15 and also overlying the compartment 15 is the horizontally disposed slot *v* positioned adjacent to the lower extremity of the stem or 55 lower portion of the slot *s* and having its outer end terminating substantially at the lower portion or foot of the slot *s*.

Disposed over the plate 17 is a transparent pane 18, and said pane 18, plate 17 and unit A are held in assembled relation by the suitable clamping members 19 coacting directly with the pane 18 and the outstanding flanges 20 carried by the casing C. The outer or free marginal portion of the unit 65 A is provided with an outstanding flange

21 which overlies the flange 20 and the marginal portions of the plate 17 overlie the flange 21 with the pane 18 disposed entirely over the plate 17. Arranged within the various compartments and operatively engaged within the sockets 16 associated therewith are the lamps 1^a, 2^a, 3^a, 4^a, 5^a, 6^a, 7^a, 8^a, 9^a, 10^a, 11^a, 12^a, 13^a, 14^a and 15^a, said lamps being of electric type and which are under control of a suitable switch for closing the circuits therefor. It is not believed necessary to illustrate and describe herein the switch as such switch may be of any desired construction which can be employed to advantage. However I have disclosed 70 a special switch for accomplishing this result in an application for patent filed on even date herewith.

When it is desired to give intention that a 75 stop is to be made the following lamps are illuminated, 1^a, 2^a, 3^a, 4^a, 5^a, 7^a, 9^a, 11^a, 13^a and 14^a resulting in light rays being disposed through the following slot or slot portions *a*, *b*, *c*, *d*, *e*, *f*, *g*, *h*, *i*, *j*, *n*, *q*, *t* and *s* as is particularly illustrated in Figure 7 of the 80 accompanying drawings.

When a turn is to be made to the right the 85 following lamps are illuminated 1^a, 2^a, 5^a, 8^a, 9^a, 13^a and 15^a which bring into conspicuity the slot or slot portions *a*, *b*, *c*, *d*, *e*, *f*, the 90 portion of the slot *g* overlying the compartment 5, *h*, *n*, *o*, *s*, *u* and *v*.

When an indication is to be given of a 95 turn being made to the left the following 100 lamps are illuminated, 1^a, 3^a, 5^a, 6^a, 7^a, 9^a, 10^a, 12^a and 13^a wherein illumination is had through the slot or slot portions *c*, *f*, *g*, *h*, *j*, *k*, *m*, *n*, *p*, *r* and *s*.

In practice when the driver of the vehicle 105 equipped with my improved signal desires to stop, he will operate the control switch to energize the group of lamps that illuminate the stencil openings that form the word "Stop". If he desires to turn the vehicle 110 to the right he will operate the switch to energize the group of lamps that illuminate the openings that form the word "Rite"; and if he desires to turn to the left he will 115 operate the switch to energize the group of lamps that illuminate the openings forming the word "Left".

The unit A is also provided in its lower portion with an elongated compartment 22 in which is centrally arranged a taillight 23, the overlying portion of the plate 17 is provided with a requisite opening 24 of desired configuration.

This application is in continuation in part 120 of my former application Serial No. 583,843, filed August 21, 1922.

From the foregoing description it is 125 thought to be obvious that a signal constructed in accordance with my invention is particularly well adapted for use by reason 130 of the convenience and facility with which

it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In an electric signal, a case provided with a series of pockets, a lamp in each pocket, and a stencil letter plate covering the pockets, said plate having letter-forming openings registering with each of the pockets and one of the pockets extending beneath and on opposite sides of another of said pockets.

2. In an electric signal, a case provided with a series of pockets of irregular shape, a lamp in each pocket and a stencil letter plate covering the pockets, said plate having letter-forming openings and some of the openings having different portions registering with different pockets.

3. A signal of the class described comprising a casing provided with a series of compartments, illuminating means within each of the compartments, and a plate disposed over the compartments, said plate having transparent portions providing a composite of a plurality of indications registering with the compartments; certain of said portions overlying a plurality of compartments.

In testimony whereof I hereunto affix my signature.

EDWIN W. McKINLEY.
